DISCHARGE TUBE ELECTRODE

Filed March 25, 1929

FIG. 1

FIG. 2

INVENTOR

Fred Hotchner

UNITED STATES PATENT OFFICE

FRED HOTCHNER, OF LOS ANGELES, CALIFORNIA

DISCHARGE TUBE ELECTRODE

Application filed March 25, 1930. Serial No. 349,647.

This invention relates to a discharge tube electrode for vapor electric devices or vacuum electric devices in which electrodes having the characteristics hereunder outlined are useful.

In my Patent No. 1,789,901 and in other previously filed copending applications I have disclosed several types of electrodes in which the discharge originates on the inside surface of a hollow cylinder and passes thru a restricted opening into the main discharge column. For the guidance of those skilled in the art I have advanced a theory of the operation of the device. It is my theory that the positive ion bombardment, heretofore considered an essential part of the mechanism of emission is reduced to a very low value in my invention and that adequate emission is secured thru electric forces. However, the theory will for a long time be controversial, and I do not limit my invention by the theory advanced in the previous disclosures or by the additional theories advanced herein. It is to be understood that this is for the guidance of those skilled in the art and that the only limitations to be placed upon this invention are those of the prior art and the appended claims.

In one previous disclosure I have explained that if the protecting shield which provides the restricted opening thru dielectric material thru which the discharge passes is so made that the opening is of capillary dimensions some very surprising and highly useful results are secured. The present invention provides that this capillary passage be at least partly thru the enclosing metal structure within which the discharge originates. Additional advantages are secured by so designing the electrode.

The primary object of this improvement is to provide for the direction of the electric force between the positive column region of the tube and the emission surfaces accurately thru the capillary in the dielectric shield thereby relieving the dielectric material around the orifice of all unnecessary electric strain. Certain mechanical improvements are also made to this end.

The discovery has been made that a capil-

lary opening of the nature disclosed will automatically maintain itself open and at the correct diameter. This is an altogether novel mechanism and not at all what might be expected from any information of the prior art. A demonstration of the action can only be made when certain rigid requirements are met and it is therefore easily understood why this phenomena has escaped previous notice.

As to my theory of the action of this device, I will point out that there is always some evaporation, however minute, of the material of the electrode. By the term evaporation I mean to include what is sometimes called sputtering of the electrode material. In the course of time a deposit will appear at some place of the evaporated material. I believe that the physical action in the conducting medium in the capillary passage is such that if deposition takes place there that it is automatically stopped at a certain point. It has been found by experience that the transportation of evaporated material thru a small capillary such as I

use can only take place under abnormal conditions, and it might therefore be inferred that a capillary of this nature will automatically "size" itself. When the necessary conditions are observed it has been found that such is the case. The essential conditions from the data now available appear to be these; that the passage thru the dielectric and conducting passage be continuous, without any space between the shield and the metal (such as might be allowed for expansion), that there be no sharp corners on the metal to which the discharge can become concentrated, and that the capillary be sufficiently small at the start to prevent

any considerable transportation of material thru the orifice and the deposition thereof on the outside. Other conditions obvious to one skilled in the art are naturally to be observed in addition. One of the objects of this invention therefore is to provide a capillary of the nature shown that will automatically close itself to a dimension small enough to prevent any transportation of evaporated material from the electrode.

Another improvement of considerable importance has been made. By providing for an opening out of the electrode chamber of extremely small section, it is possible to make 5 the chamber in the form of a sphere instead of a cylinder. The object of this is to provide for a uniform electric force over practically the entire emission surface and to eliminate the movement of ions along the 10 axis of the electrode as can take place in a cylinder. The disturbance, if any, caused by the opening out of the chamber is very slight and it has been found that the process of evaporation and deposition automatically 15 corrects this condition so far as practical operation is concerned.

It will be understood that the discharge 20 can not take place inside of the capillary under normal operating conditions. Other 25 objects of the invention will be apparent to those skilled in the art from the following specification.

A further object is to provide a new and 25 very simple method of protecting the lead in conductor from a discharge. The device here used provides a discharge tight joint which isolates the region behind the electrode from the main portion of the tube. The joint in practice is probably in most 30 cases also gas tight and inasmuch as it is necessary that the gases in the region behind the electrode be disposed of in pumping the tube I make use of a further novel device to this end. I have discovered that 35 a very small hole thru the material of the electrode leading from this space into the chamber within the electrode will permit the complete evacuation of the region behind the electrode and still will permit little 40 if any discharge taking place from the exposed metal parts in that region when first starting the tube and none at all after the tube has burned in.

In the drawings, Figure 1 is a sectional 45 view of the present invention as applied to an electrode similar to those shown in the previous disclosures.

Figure 2 is a sectional view of this invention in the form of an electrode in which full 50 utilization is made of the advantages of the capillary passage to affect advantageous changes in other features of the device.

In the view in Figure 1, numeral 1 indicates the electrode end of a discharge tube 55 in which 2 indicates the reentrant stem having the lead in conductor 3 sealed therein; 4, the electrode proper; and 5, the shield.

The electrode proper 4 has the general shape of a capsule, all sharp corners are 60 eliminated on the inside in order that the discharge may not become concentrated at any particular point. The emission takes place from the inside surface and the discharge passes out thru the capillary opening 65 6. The opening 6 communicates with the

capillary opening 7 in the shield 5. The spring 16 pushes the electrode and the shield up against the protrusion 8 in the wall of the tube proper. In this instance the lead in conductor 3 has a bent-over portion 9 which makes a pressure contact with the end 10 of the electrode.

In order to provide for expansion the electrode is slightly smaller in outside diameter than the inside of the shield, and the shield likewise has a slight clearance in the tube. A novel device is used to protect the lead in conductor. The technique of forming the protrusion in the tube is given in a previous disclosure and is repeated hereunder as modified by improvements of this record.

The final form of the slope 11 of the protrusion 8 is such that it makes intimate contact with the surface 12 of the head 13 of the shield 5 without fusing thereto. This contact should preferably be confined to an area close to the apex 14 in order that no strain from expansion will be placed on the tube. The fit should be so intimate that no discharge can pass thru to the lead in wire. I have found that such joints if properly executed are entirely adequate to prevent a discharge from passing to the lead in wire and tubes so made may be easily manipulated thru the degasifying process without breaking the glass at the joint. I believe this to be an entirely new result in the art and one which is of great value. While in my previously filed application No. 341,320 I have shown in Figure 2 an internal protrusion in the wall of the tube against which an electrode assembly is made to bear for the purpose of mechanical support I had not discovered that such joints could be so improved as to be entirely adequate of themselves to stop the discharge and provided for that purpose a body of porous material between the lead in wire and the main chamber of the tube.

In order that the region behind the electrode can be freed of gases during the pumping process, a capillary opening 15 of extremely small cross-section is provided thru the wall of the electrode. Experimental evidence has shown that this passage will not from a practical point of view cause sufficient discharge to take place from behind the electrode to cause any trouble. In operation it often becomes closed up.

The functioning of the capillary 6 has developed very satisfactory features of operation. The discharge takes place from the inside surfaces of the capsule and passes out thru the capillary freely without closing up the capillary as long as the outside of the capillary opening is well protected from discharge. It is essential that the openings thru the metal and the shield fit together well without any edge or point to which the discharge can become concentrated and start

a destructive process. It appears also to be essential that the curves of the surfaces in contact with the discharge be smooth and regular and conform to natural lines of flow.

5 In the fabrication of the assembly, the lead in conductor is made up in the stem in the usual manner and sealed in the end of a short piece of lead glass tube. The shield and the electrode and spring are placed in 10 the tube from the open end. The shield is made of material, such as Pyrex glass, of a high melting point compared with lead glass. A male tool is introduced in the tube from the open end and the loose parts are 15 depressed until the desired compression is placed on the spring. The glass of the tube around the region of the desired protrusion is then heated to a temperature sufficient to render it plastic but not fluid and by the use 20 of suitable tools it is thickened by pressing the tube together and worked into its final form. It is essential that the shield and the protrusion should not be stuck together. This can be prevented by suitable manipulation 25 during the heating process.

In the form of the invention shown in Figure 2 advantage is taken of the discoveries stated above to effect further improvements in the design. The electrode proper 20 is in the form of a hollow sphere. This provides for a nearly uniform electric force over the entire active surface. It also reduces further the movement of positive ions as compared with the hollow cylindrical 25 type of electrode. With the cylindrical electrode there is a component parallel with the axes of the cylinder which results in a certain amount of disintegration at the end of the cylinder.

40 The shield 21 is made with freely flowing lines in order that the material may be easily manipulated in manufacturing the same and finished accurately to the desired shape. It is to be noted that when the shield is made from material such as glass that the shape of the finished shield is very close to that which is naturally taken by a piece of heated glass tube in a semi-fluid state. It is thus possible to make the shield of very 45 high melting point material and manipulate it into final shape with little effort. The bulbous end 22 of the shield fits into the ring depression 23 in the outside of the electrode around the opening. The feather edge 24 of the capillary tube thus runs off into a natural intimate contact with the passage thru the shield. The shapes thus given to the electrode and the shield are those most 50 easily attained by methods well known in the art and which leave the material in a condition free from strain, dense and smooth surfaced.

The method of forming the protrusion 25 in this case is similar to that given above, 55 there being an accumulation of glass

brought about in the region of the protrusion. It will be noticed that the shape assigned to the tube at this point is such as to allow the material to cool without internal strains. An evenly expanding passage is 70 provided for the discharge to follow between the capillary and the tube proper.

The method features hereinbefore disclosed are not claimed in this application but are claimed in my copending application Serial No. 528,833. 75

The electrode is provided with a capillary opening 31 for the purpose of providing an escape for the gas behind the electrode. The spring 26 is made in the form of a helix, 80 the wide end bearing on the glass at the end of the stem 27, and the narrow end bearing on the electrode. The lead in conductor 28 has a slack loop 29 and the end 30 is pinched onto the spring to insure a good contact. 85

The electrodes of the present invention are characterized by the fact that the capillary orifice is interposed between the Faraday dark space region and the emission surface of the electrode. To this I ascribe 90 partially the different behavior of the discharge in passing thru the orifice of my device and the reported behavior of discharges passing thru orifices interposed in the positive column proper. The electrodes 95 of my device do not evidence a rectifying action and do not appear to develop any unusual heating effect.

It is preferred that the capillary portion of the orifice be very short and that from 100 the narrowest point it open up rapidly into the electrode chamber and into the main chamber of the tube and that the walls of the passages follow natural lines of flow. The expression "natural lines of flow" in a 105 generic sense applies to lines of easy curvature leading to and away from the narrowest point of the orifice much as lines would be drawn to provide the best passage thru an orifice for a flowing body of fluid. While 110 there is an enormous difference in the physical nature of a flowing body and the flow of current by ionization thru a stationary body I have discovered that for some still unknown reason improved results can be 115 secured in the latter case by designing the walls of passages in the manner described.

The term "ionization conductor" as herein used refers to any medium in which radiation is generated by ionization caused by 120 the flow of an electric current therethru. Typical of such mediums are bodies of the noble gases at low pressure or the vapors of metals such as mercury.

The various features of the invention I believe to be all new either as used separately 125 or in combination and have many possible applications in discharge tube devices. The invention is not limited to the particular embodiment shown nor to devices in 130

cluding all of the illustrated features but may on the contrary be variously embodied singly or in groups in various types of discharge tube devices within the purview of the following claims.

Having thus described my invention, what I claim is:

1. In a discharge tube, a hollow electrode from the inside surface of which the emission takes place, and a passage of capillary cross-sectional dimension thru the wall of said electrode thru which the discharge passes into the tube proper.

2. In a discharge tube, a hollow electrode, the inside surfaces of which are of conducting material, and a discharge passage from the inside of said electrode to the discharge column proper, the walls of said passage being of conducting material and in contact with the aforesaid inside surfaces of said electrode, the cross section of said passage being reduced to a diameter sufficiently small to prevent a discharge taking place from the walls thereof without preventing the passage of a discharge therethru to the chamber within said electrode.

3. In a discharge tube, a hollow electrode from the inside surface of which the emission takes place, and a passage of capillary cross-sectional dimension thru the material of the wall of said electrode thru which the discharge passes into the tube proper and a shield of dielectric material having a like passage which forms a continuation of the first mentioned passage, said shield being positioned to protect the material of said electrode at the end of the first said passage from the action of the discharge and direct the discharge into said passage.

4. In a discharge tube, a hollow electrode, from the inside surface of which the emission takes place, a passage of capillary cross-sectional dimension thru the material of the wall of said electrode, a shield of dielectric material having a passage of like dimensions said shield directly abutting the said electrode, said passage forming a continuous passage for the discharge from the inside of said electrode to the discharge column proper, the curvature of the walls of said passages being such as to follow natural lines of flow.

5. In a discharge tube, a hollow spherical electrode from the inside surface of which the emission takes place, a passage of capillary cross-sectional dimension thru which the discharge passes into the tube proper and dielectric shielding means outside said electrode to direct the discharge thru said passage and prevent the discharge from attacking the outside surfaces of said electrode.

6. In a discharge tube, a hollow electrode, an opening thru the wall of said electrode, the size of said opening being in the order of a capillary passage, a shield of dielectric ma-

terial, an opening thru said shield of a size in the order of a capillary passage, said electrode and said shield being so fashioned and assembled with relation to each other and the envelope of said tube that the both said openings are in direct communication with each other and the discharge in the main discharge chamber of the said tube is prevented by said shield from reaching any portion of said electrode except the inside surfaces of said electrode by way of the said openings in said electrode and said shield.

7. In a discharge tube, an elongated tubular envelope, an inwardly extending protrusion formed from the material of the wall of said tube and comprising a part thereof, an electrode assembly in said tube positioned in the portion of said tube with respect to said protrusion distant from the main discharge column portion of said tube, a portion of said electrode assembly bearing against the said protrusion and forming a discharge-tight joint therewith.

8. In a discharge tube, an elongated tubular envelope, an inwardly extending protrusion formed from the material of the wall of said tube and comprising a part thereof, an electrode assembly in said tube positioned in the portion of said tube with respect to said protrusion distant from the main discharge column portion of said tube, a portion of said electrode assembly bearing against the said protrusion and forming a discharge-tight joint therewith, and a passage thru said electrode assembly providing communication between the main chamber of said tube and the region behind said electrode the size of said passage being sufficiently small to prevent a material discharge taking place from the exposed metal parts in the last said region.

9. In a discharge tube, a hollow electrode from the inside surface of which the emission takes place, and a passage of capillary cross-sectional dimension thru the wall of said electrode thru which the discharge passes into the discharge tube proper, all of the surfaces inside of said electrode being rounded and virtually free from corners.

10. In a discharge tube, an envelope, an ionization conductor therein, a body of conducting material within said envelope, and a passage thru said body of conducting material thru which the discharge passes, the dimensions of said passage being such that no emission takes place from the walls of said passage.

11. In a discharge tube, an elongated tubular envelope, an inwardly extending protrusion formed from the material of the wall of said tube and comprising a part thereof, an electrode assembly in said tube positioned in the portion of said tube with respect to said protrusion distant from the main discharge column portion of said tube, a por-

tion of said electrode assembly bearing against the said protrusion and forming a discharge-tight joint therewith, a lead-in conductor sealed thru said envelope at a 5 point in the envelope behind said electrode with respect to said protrusion, means to press said electrode assembly against said protrusion, and a passage thru said electrode assembly providing communication between 10 the main chamber of the said tube and the region behind said electrode.

12. In a discharge tube, a cylindrical shield of dielectric material, one end of said shield being formed into practically a closure 15 for said cylinder, there remaining an opening of practically capillary dimensions thru said closure at or near the axis of said cylinder, and a hollow electrode having an opening of like dimensions positioned within 20 said shield, both of said openings being in direct communication.

13. The method of preventing the migration 25 of evaporated material from an electrode in a discharge tube, which consists in passing the discharge thru a passage of capillary cross-sectional dimension formed thru the material of the wall of said electrode.

14. The method of preventing the migration 30 of evaporated material from an electrode in a discharge tube, which consists in passing said discharge thru a capillary passage formed thru the material of the wall of said electrode.

35 15. In a discharge tube, a shield of dielectric material, a passage of capillary dimensions thru said shield, the material around said passage following easily curved lines, and a hollow electrode having an opening 40 of capillary dimensions, the material of said electrode around said passage running off into the said passage thru said shield forming a continuous passage thru the wall of said electrode and thru said shield.

45 16. In a discharge tube, an envelope of vitreous material, a member within said envelope of dielectric material forming a discharge barrier between two regions within said tube, said member and said envelope 50 being joined together without fusion in a joint sufficiently intimate to prevent the passage of a discharge therebetween, the entire contacting area of the envelope at said joint being concaved towards the contacting portion of said barrier member, and means to press said barrier member into said joint.

55 17. In a discharge tube, an envelope of vitreous material, and a member of vitreous material within said envelope extending between opposite walls of said envelope and forming a discharge barrier between two regions within said envelope, said barrier member being formed of material of a lower coefficient of expansion than the material of 60 said envelope and fitting within said envelope and conforming to the contour of the wall thereof with a discharge tight joint.

65 18. In a discharge tube, an elongated envelope, an electrode assembly near one end of said envelope fitting the walls of said envelope with a discharge tight joint, there being a chamber within said electrode assembly and a capillary passage thru the material of the electrode communicating with the region behind said electrode assembly thereby providing a passage thru which the atmosphere in said region may be evacuated thru the electrode assembly.
